United States Patent Office.

A. F. CROSMAN, OF STEAMER OSSIPPEE, UNITED STATES NAVY.

Letters Patent No. 70,813, dated November 12, 1867.

IMPROVED BOAT-HOISTING APPARATUS.

The Schedule referred to in these Letters Patent and making part of the same.

TO ALL WHOM IT MAY CONCERN:

Be it known that I, A. F. CROSMAN, of Steamer Ossipee, North Pacific Squadron, United States Navy, have invented a new and improved Boat-Hoisting Apparatus; and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

This invention is designed to facilitate the hoisting of small boats at the sides of ships and other vessels. The invention consists in a novel arrangement of the davit-tackles, as hereinafter fully shown and described, whereby the tackle of both davits are operated, and the boat hoisted or lowered by the manipulation of a single rope. The invention further consists in a novel means for releasing simultaneously both ends of the boat from the hooks of the tackle-blocks, when the boat is lowered, so as to reach the water, and thereby prevent the capsizing of the boat, a contingency of not unfrequent occurrence when the water is rough. In the accompanying sheet of drawings—

Figure 1 is a side view of a portion of a ship or other vessel provided with my improvement.

Figure 2, a section of the same, taken in the line *x-x*, fig. 1.

Figure 3, a section of the same, taken in the line *y-y*, fig. 1.

Similar letters of reference indicate like parts.

A represents a portion of the side of a vessel, and B B the davits attached thereto as usual, and provided with the ordinary davit-tackle C C. These parts being old and well known, do not require a special description. Each tackle C, however, instead of being operated separately, as is now the case, has its ropes *a a* attached to drums D D, which are secured on one and the same shaft E, the bearings *b* of said shaft being secured to the outer side of the vessel. The ropes *a a* are attached to the drums D D, so that they will be wound around the same in opposite directions, and between the two drums D D there is an intermediate drum, F, around which a rope, G, passes. The shaft E is midway between the two davits B B, and it will be seen that when the rope G is pulled, and the drums D D consequently turned, the two davit-tackles will be operated simultaneously, and the boat H, which is attached to the hooks *c* of the lower tackle-blocks I, will be raised or lowered by the manipulation of the rope G only.

The boat H is suspended or attached to the hooks *c* of the lower tackle-blocks as follows: To the bottom of the boat H, near each end of the same, there is attached a link, J, and a similar link, K, is fitted on the hook *c* of the blocks I. On each link K a hook, L, is fitted, the links passing through the hooks at their angles. To the ends of the shanks of the hooks slotted bars or narrow links M are pivoted, one to each. These bars or links serve as "mousings," and retain or hold the links J on the hooks L, one end of the "mousings" being over the ends of the hooks L, and the opposite ends retained by hooks N, which are suspended to thwarts in the boat, and have each a rope or chain, *d*, attached, which may pass over pulleys or through guides *e* at the under sides of the thwarts, and are attached to a vertical bar, *f*, which is fitted in a guide, *g*, at the centre of the boat, and retained in position by a pin, *h*. When the boat is lowered so that it touches the water, the pin *h* is withdrawn from the bar *f*, and the inner ends of the "mousings" M are thereby released, and the links J, under the weight or gravity of the boat and its load, instantly and simultaneously become detached from the hooks L.

Having thus described my invention, I claim as new, and desire to secure by Letters Patent—

1. The drums D D upon the shaft E, secured to the side of the vessel between the davits, and provided with a rope, G, passing through the side of the vessel, all arranged as described, whereby the manipulations of the rope G operate the tackle-ropes *a a* simultaneously, as herein shown and described.
2. The arrangement of the links J K, hooks L, metallic mousings M, hooks N, and vertically sliding bar *f*, for detaching the boat from the tackle-blocks, as herein shown and described.

The above specification of my invention signed by me this eleventh day of June, 1867, at Panama.

A. F. CROSMAN.
